UNITED STATES PATENT OFFICE.

GEORGE HENRY WHEARY, OF RACINE, WISCONSIN, ASSIGNOR TO WHEARY TRUNK COMPANY, OF RACINE, WISCONSIN, A CORPORATION OF WISCONSIN.

WARDROBE TRUNK.

Original application filed July 19, 1919, Serial No. 311,925. Divided and this application filed January 18, 1924. Serial No. 637,057.

To all whom it may concern:

Be it known that I, GEORGE HENRY WHEARY, a citizen of the United States, and resident of Racine, in the county of Racine and State of Wisconsin, have invented new and useful Improvements in Wardrobe Trunks, of which the following is a description, reference being had to the accompanying drawings, which are a part of this specification.

This invention relates to improvements in wardrobe trunks, and is a divisional application of application filed July 19th, 1919, Ser. No. 311,925.

15 Wardrobe trunks of the better class are usually divided vertically into two parts to form a wardrobe section and a drawer section. The two parts are hinged together to swing horizontally to open or closed position. The wardrobe section is provided with garment hangers for suspending outer wearing apparel thereon, and the other section is provided with drawers for holding other articles of wear.

20 Trunks of this type are usually formed of wood covered with fiber, and the fiber at the abutting edges of the section is usually folded inwardly over the section edges to form a finish, and the inner portions of the sections are usually lined with a suitable fabric to finish the interior edges of the fiber.

A further object of the invention is to provide a wardrobe trunk having an improved form of valance which forms a finish 35 for the edge portions of the trunk sections and thereby permitting the elimination of interior linings.

A further object of the invention is to provide a wardrobe trunk having an improved form of valance which forms a dust 40 proof joint between the edges of the two trunk sections and also serves to reinforce the edges thereof.

A further object of the invention is to provide a wardrobe trunk having a combined collar and garment hanger track formed of metal.

A further object of the invention is to provide the wardrobe section of a wardrobe 50 trunk with a removable means for firmly and yieldingly holding the hangers and gar-

ments carried thereby in position within the said section.

With the above and other objects in view the invention consists of the improved wardrobe trunk and its parts and combinations as set forth in the claims, and all equivalents thereof.

In the accompanying drawings in which the same reference characters indicate the same parts in all of the views:

Fig. 1 is a top view of the trunk section in closed positions, the top cover being in open position;

Fig. 2 is a vertical sectional view of the upper portion of the wardrobe section of the trunk;

Fig. 3 is a vertical sectional view of the upper portion of the wardrobe section, the top cover removed; and

Fig. 4 is a detail front view of the extension rails.

Referring to the drawings the numeral 18 indicates the wardrobe section and 19 the drawer section of a wardrobe trunk. The two sections are hinged together to swing horizontally to open or closed position, and the wardrobe section is provided with a top cover 20 which is hinged to the upper portion of the drawer section and swings forwardly over the wardrobe section. The wardrobe section is provided with garment hangers 21.

The edge portions of the trunk sections are provided with coacting valance members 36 and 37 which are formed of strips of sheet metal bent to channel portions 36' and 37' into which the edge portions of the trunk sections extend.

The open end of the wardrobe section and its cover are also provided with valance members similar to the ones described.

The open end of the wardrobe section is also provided with a metal U-shaped collar 40 which is fastened to the inner surfaces of the valance member 36 and forms part thereof. The said collar is therefore connected to the wardrobe section and is inwardly offset and projects upwardly therefrom to form the trunk collar and garment hanger tracks 45 upon which the garment hangers 21 are slidably mounted. The upper edge portions of

the combined collar and track are curved inwardly and downward as indicated by the numeral 41 to form a bearing surface for the garment hangers 21. The outer end portions of the collar and track have extension tracks 42 hinged thereto which are adapted to swing horizontally outwardly to open position to permit convenient access to the garments on the hangers. In folded position, 10 as shown in Fig. 1, the extension hangers serve to hold the garment hangers in position.

What I claim as my invention is:

1. A garment hanger bracket for trunks 15 comprising a channelled supporting element adapted to be mounted in embracing relation about the marginal edge-portions of the open end of the body-section of a trunk, and

means extending from said supporting element for the suspension therefrom of garment hangers. 20

2. A garment hanger-bracket for trunks comprising a channelled supporting element consisting of a rear member and a pair of side-members extending at right angles from 25 said rear member, said rear member and said side members being adapted to be mounted in embracing relation about the marginal edge-portions of the open end of the body-section of a trunk, and means extending 30 from said rear member for the suspension therefrom of garment hangers.

In testimony whereof, I affix my signature.

GEORGE HENRY WHEARY.
